(74) Attorney, Agent, or Firm — LEX IP MEISTER, PLLC

(57) **CLAIM**

The ornamental design for a juice extractor, as shown and described.

DESCRIPTION

The patent or application file contains at least one drawing executed in color. Copies of this patent or patent application publication with color drawing(s) will be provided by the Office upon request and payment of the necessary fee.

1. Juice extractor

1.1 : Perspective

1.2: Front

1.3: Back

1.4: Left

1.5: Right

1.6: Top

1.7: Bottom

The portions colored in blue in the reproductions illustrate portions of the juice extractor that form no part of the claimed design.

1 Claim, 7 Drawing Sheets
